INVENTOR,
Samuel C. Allen,
BY *Howard J. Smith*,
Esq. ATTORNEY

UNITED STATES PATENT OFFICE

SAMUEL C. ALLEN, OF NEAR DAYTON, OHIO, ASSIGNOR TO THE DAYTON STEEL
RACQUET COMPANY, OF DAYTON, OHIO, A CORPORATION OF OHIO

METAL ARROW

Application filed July 2, 1927. Serial No. 203,240.

This invention relates to new and useful improvements in metal arrows.

It is the principal object of my invention to provide a metal arrow, preferably constructed of steel, which combines lightness and rigidity, and is straight and true to insure a more perfect flight than a wood arrow. My metal arrow also has sufficient spine to prevent bending when released from the bow, thereby avoiding a lateral or vertical deflection so common with arrows made of wood at the start of their flight.

It is another object of my invention to provide for arrows a tubular metal shaft that is sheared at one end to provide axial slits to receive the feathers. These feathers are free to be slipped endwise into the slits in the shaft, so that the vein of each feather will be on the inside of the shaft. Each feather is thus firmly secured to the shaft with the same rigidity as any other feather, to give the arrow a more perfect flight.

It is still another object of my invention to provide a metal pile which may be easily inserted into the anterior end of the tubular steel shaft and glued there.

Another object of the invention is to provide for the arrow a nock which may be made of bakelite fiber, aluminum, or other suitable material, preferably in a punch press. The nock is formed for easy insertion in the feathered end of the tubular metal shaft and is held in place by glue or a like substance.

One of the important features of my metal arrow is, that the feathers, pile and nock, frequently injured in flight, are easily replaced.

Other important and incidental objects will be brought out in the following specification and particularly set forth in the subjoined claims.

In the accompanying drawings illustrating my invention, Figure 1 is a plan view of my improved metal arrow. Figure 2 is a longitudinal sectional view taken through the pile. Figure 3 is a cross sectional view taken through the arrow and feathers on the line 3-3 of Figure 1, showing the veins of the feathers within the tube. And Figure 4 is a longitudinal sectional view taken through

the feathered end of the arrow, showing how the nock is secured therein.

In the accompanying drawings illustrating my invention, the numeral 1 designates a metal shaft, preferably made of seamless steel tubing. Such a shaft combines lightness and rigidity, and insures a more perfect flight than a wood shaft. Furthermore, there is no warping quality in steel as against wood. It also has sufficient spine to prevent bending when released from the bow, thereby avoiding a lateral or a vertical deflection so common with arrows made of wood at the start of their flight.

The metal tube 1 is formed at one end with axial slits 2, preferably three in number, that are spaced 120 degrees apart to receive feathers 3. These feathers are adapted to be slipped endwise into these slits, with the veins of the feathers positioned within the tube. Each feather will thus be held by its vein to the shaft 1 with the same rigidity as all the other feathers. (See Figures 1 and 3.)

Adapted to be inserted in the feathered end of the tube 1 is a nock 4 that may be constructed in the form shown in Figure 4 of bakelite, aluminum or other suitable material. The inner part of the nock is of reduced diameter for insertion in the end of the tube, where it is glued in place after the feathers 3 have been inserted in the slits 2.

The above method of securing the feathers and the nock to the shaft makes them easily replaceable if injured in any way.

In Figure 2 I have shown a pile 5 which preferably consists of a steel piece turned or punch pressed to cylindrical form with a conical head 6 and a rear portion 7 of reduced diameter for insertion in the anterior end of the tubular shaft 1, where it is preferably glued in place.

It will be apparent that the different parts of my metal arrow may be economically constructed and easily assembled to reduce the cost of production to the minimum. The pile, feathers and nock may also be easily replaced in the tubular shaft when injured.

When assembled, the metal arrow will be light, well-balanced, non-warping, straight

and true, and will have a more perfect flight than a wood arrow.

Having described my invention, I claim:

1. An arrow having a tubular metal shaft formed with axial slits at its feathered end, and feathers insertable endwise into said slits, the veins of the feathers being within the shaft and wider than the slits for the purpose specified.
- 10 2. An arrow having a tubular metal shaft formed with axial slits at its feathered end, feathers insertable endwise into said slits, and a nock insertable into the feathered end of said shaft after the feathers are in place within said slits.
- 15 3. An arrow comprising a tubular, metal shaft, a pile removably inserted in the anterior end of said shaft and a nock removably inserted in the other end of said shaft.
- 20 4. An arrow for archery comprising a metallic tubular shaft, a pile having a portion telescoped in one end of the tubular shaft, a nock having a portion telescoped into the opposite end of the shaft, said pile and said nock sealing both ends of the shaft.
- 25

In testimony whereof I have hereunto set my hand this 23rd day of June, 1927.

SAMUEL C. ALLEN.
